UNITED STATES PATENT OFFICE

2,181,417

BOWED CURTAIN FIXTURE

James H. Boye, Chicago, Ill., assignor to James H. Boye Manufacturing Company, Chicago, Ill., a corporation of Illinois

Application December 16, 1938, Serial No. 246,056

9 Claims. (Cl. 156—22)

This invention relates to the art of curtain and drape hangers, and has reference more particularly to a modern type of such devices known as bowed curtain fixtures wherein the rod from which the curtain or drape is hung is curved or bowed instead of being straight, as in the older styles.

Some users of bowed curtain hangers prefer to mount them with the rod horizontal. Others prefer to mount them with the rod tilted upwardly. Obviously, a desirable type of such hangers is one that can be mounted either horizontally or in a more or less tilted position, since this conduces to economy and standardization in manufacture, reduces the number and variety of stock required to be carried by the dealer, and affords to the user the advantage of obtaining either effect with a single fixture.

In my pending applications, Serial No. 239,615, filed November 9, 1938, now U. S. Patent No. 2,150,104 of March 14, 1939, and Serial No. 243,299, filed December 1, 1938, I have disclosed bowed curtain fixtures that are adjustable between horizontal and tilted positions, the adjustment being effected by means of connections including horizontal pivots between the ends of the rod and its supporting brackets, and means for clamping the ends of the rod in adjusted position. My present invention secures the same result, but on a different mechanical principle, each end of the rod being provided with two fixed vertically spaced bracket engaging members and the bracket being provided with parts cooperating with said bracket engaging members and adjustable vertically relatively to each other so that the rod may be supported either horizontal or in a more or less tilted position.

The general object of the invention has been to provide a simple and inexpensive bowed curtain rod and supporting brackets therefor wherein in the means for adjusting the rod to different positions and locking the adjusting means in adjusted positions shall be incorporated wholly in the brackets.

Practical embodiments of the principle of the invention are illustrated in the accompanying drawing, in which—

Fig. 1 is a perspective elevation of an extensible bowed curtain rod shown in upwardly tilted position and mounted at its ends on my improved supporting brackets.

Fig. 2 is an enlarged vertical section taken on the line 2—2 of Fig. 1, showing in full lines a tilted position of the rod and the position of an adjustable member of the bracket that cooperates

with the rod in such tilted position, and in dot and dash lines a horizontal position of the rod and the position of the adjustable bracket member that permits the rod to assume such horizontal position.

Fig. 3 is a horizontal section taken on the line 3—3 of Fig. 2.

Fig. 4 is a horizontal section taken on the line 4—4 of Fig. 2.

Fig. 5 is a horizontal section taken on the line 5—5 of Fig. 2.

Fig. 6 is a front perspective view of a modified form of bracket.

Fig. 7 is a vertical section taken on the line 7—7 of Fig. 6.

Fig. 8 is a somewhat enlarged vertical section taken on the line 8—8 of Fig. 6.

Referring to the drawing, 10 designates a conventional top member of a window or door frame on which the fixture is mounted. 11 and 12 designate outer and inner telescoping sections of an extensible curtain rod of the well known "flat" type, said sections being curved lengthwise producing what is known as a bowed rod. Mounted in the outer end of each rod section is a longitudinally curved and transversely flat shank 13 that is locked in place by mashing the marginal beads 14 down onto the top and bottom edges of the shank. The shank projects beyond the end of the rod proper, and on the projecting portion is formed a hook 15 that is continuous with the upper marginal portions of the shank, and a straight stop finger 16 that is continuous with the lower marginal portion of the shank and extends some distance beyond the hook 15.

The rod-supporting bracket comprises a flat base plate 17 that has holes 18 and 19 in its upper and lower ends to receive fastening screws 20 and 21. Cut and bent forwardly from the base plate 17 is a horizontal lug 22 through which is formed a hole 23 constituting an eye to receive the hook 15.

In the form of bracket shown in Figs. 1 to 5 inclusive, 24 designates a slide that overlies the front face of the base plate 17 and is formed with flanges 25 on its vertical edges that slidably engage the vertical edges of the base plate 17. The slide 24 is permanently attached to the base plate with capacity for limited vertical adjustment by a rivet stud 26 mounted in the base plate some distance below the lug 22 and extending through a vertical slot 27 in the slide and having a head 28 overlapping the slot 27. Below and in line with the slot 27 is a second

slot 29 that registers with the lower screw hole 19 and receives the lower fastening screw 21. On the upper end of the slide 24 is a forwardly bent flat horizontal stop plate 30 preferably formed 5 with a V-notch 31 in its front edge; and on the lower end of the slide 24 is a lip 32 that constitutes a convenient finger-hold when adjusting the slide. The slide is adjusted vertically by slightly backing off the screw 21, shifting 10 the slide up or down to the desired distance, and then retightening the screw.

With the slide adjusted to the position shown in full lines in Fig. 2, the rod end is entered on the bracket by first entering the hook 15 through 15 the hole 23, and then lowering the rod until the finger 16 engages with the notch 31 of the stop plate 30. This holds the rod in the tilted position shown in Fig. 1 and in full lines in Fig. 2. If a higher tilt of the rod is desired, this may 20 be effected by lowering the slide. If a lower tilt is desired, this may be effected by slightly raising the slide. If a horizontal position of the rod is desired, as shown by dot and dash lines in Fig. 2, the slide is raised to the position indicated by dot and dash lines, and in this position the stop finger 16 does not contact with the stop plate 30, but underlies the latter and abuts at its free end on the face of the slide just below the stop plate. It will be observed that in all 30 positions of the rod the hook constitutes a tension member and the finger constitutes a thrust member or strut to support the weight of the rod and the curtain on the brackets.

Figs. 6, 7 and 8 illustrate a slight modification 35 of the slide. In these views the slide 33 is somewhat shorter than the slide 24 and is not engaged with the lower fastening screw 21. In lieu of the rivet stud 26, there is employed a machine screw 34 that is secured in the base plate 17 and passes 40 through a vertical slot 35 in the slide 33. Manifestly, by slightly backing off the screw 34, the slide may be adjusted vertically, and then secured in place by re-tightening the screw 34. To aid in holding the slide in adjusted position, I prefer- 45 ably form on the back of the slide at one edge of the slot 35 a vertical group of narrowly spaced horizontal grooves 36 (Fig. 8), and on the front face of the back plate 17 I form a tongue 37 that is engaged with one of the grooves when the 50 screw 34 is tightened. Of course, the grooves might be formed in the base 17 and the tongue on the slide.

The V-notch 31 in the stop plate 30 is not in- 55 dispensable and might be omitted, making the front edge of the stop plate square; but it is preferably employed as forming a sort of rod centering device, especially when used with an extensible rod, as shown.

From the foregoing it will be seen that the 60 means for adjusting the rod between a horizontal position and various upwardly tilted positions is located wholly in the rod supporting brackets, and does not depend on any horizontal pivots between the ends of the rod and their brackets.

While the inserted shanks 13 are preferably 65 employed, it is evident that they might be omitted, and the hook and stop finger formed on a projecting portion of the body of the rod itself.

Obviously, the structural details shown and 70 described may be varied without sacrificing any of the described advantages. Hence, I do not limit the invention to the particular embodiments presented for purposes of illustration, but reserve 75 all such variations, modifications and mechanical

equivalents as fall within the spirit and coverage of the claims.

I claim:

1. In a curtain fixture of the type described, the combination with a bowed curtain rod carrying 5 on each end thereof a hook and, beneath said hook, a finger, of brackets each having an eye for engagement with said hook and, beneath said eye, a vertically adjustable stop member adapted to contact with said finger in various upwardly tilted positions of said rod.

2. In a curtain fixture of the type described, the combination with a bowed curtain rod carrying 15 on each end thereof a hook and, beneath said hook, a finger, of brackets each having an eye for engagement with said hook and, beneath said eye, a vertically adjustable stop member adapted to contact with said finger in various upwardly tilted positions of said rod, said stop member being capable of adjustment to a height such that when 20 said rod is horizontal said finger may underlie said stop member and abut at its free end against said bracket.

3. In a curtain fixture of the type described, the combination with a bowed curtain rod, of flat shanks secured in the ends of said rod, each of 25 said shanks projecting beyond the end of the rod and formed with a hook and, beneath said hook, a finger, and brackets each having a horizontal lug formed with an eye for engagement with 30 said hook and, beneath said lug a vertically adjustable stop member adapted to contact with said finger in various upwardly tilted positions of said rod.

4. In a curtain fixture of the type described, the combination with a bowed curtain rod, of flat shanks secured in the ends of said rod, each of 35 said shanks projecting beyond the end of the rod and formed with a hook continuous with its upper edge portion and with a straight finger con- 40 tinuous with its lower edge portion, and brackets each having a horizontal forwardly projecting lug formed with an eye for engagement with said hook and, beneath said lug, a horizontal vertically adjustable forwardly projecting stop plate 45 adapted to contact with said finger in various upwardly tilted positions of said rod.

5. A specific embodiment of the combination defined in claim 4, wherein the stop plate is capable of adjustment to a height such that when 50 the rod is horizontal the finger may underlie the stop plate and abut at its free end against the bracket.

6. A specific embodiment of the combination defined in claim 4, wherein the stop plate has a 55 V-notch in its forward edge to center the rod.

7. A curtain rod supporting bracket, comprising 60 a base plate having a forwardly projecting lug apertured to engage a hook on the end of the rod, a slide mounted on said base plate carrying a forwardly projecting stop plate adapted to contact with a stop finger on the end of the rod, and means for securing said slide on said base plate in various vertically adjusted positions.

8. A curtain rod supporting bracket, comprising 65 a base plate having holes for fastening screws at its upper and lower ends, a forwardly projecting lug apertured to engage a hook on the end of the rod, and a headed stud below said lug, and a 70 slide mounted on said base plate having on its upper end a forwardly projecting stop plate adapted to contact with a stop finger on the end of the rod, said slide being vertically slotted to straddle said stud and the lower fastening screw. 75

2,181,417

3

9. A curtain rod supporting bracket, comprising a base plate having holes for fastening screws at its upper and lower ends, a forwardly projecting lug apertured to engage a hook on the end 5 of the rod, and a clamp screw below said lug, and a slide mounted on said base plate having on its

upper end a forwardly projecting stop plate adapted to contact with a stop finger on the end of the rod, said slide being vertically slotted to straddle the neck of said clamp screw.

CERTIFICATE OF CORRECTION.

Patent No. 2,181,417.

November 28, 1939.

JAMES H. BOYE.

It is hereby certified that error appears in the printed specification of the above numbered patent requiring correction as follows: Page 1, first column, line 21, for the patent number "2,150,104" read 2,150,204; and that the said Letters Patent should be read with this correction therein that the same may conform to the record of the case in the Patent Office.

Signed and sealed this 9th day of April, A. D. 1940.

(Seal)

Henry Van Arsdale,
Acting Commissioner of Patents.
